UNITED STATES PATENT OFFICE.

JOHN GEORGE ROBINSON, OF MANCHESTER, ENGLAND.

STEAM SUPERHEATER FOR LOCOMOTIVE AND OTHER SMOKE-TUBE BOILERS.

1,077,641.

Specification of Letters Patent.

Patented Nov. 4, 1913.

Application filed July 26, 1912. Serial No. 711,681.

To all whom it may concern:

Be it known that I, JOHN GEORGE ROBINSON, a subject of the King of Great Britain and Ireland, residing at Manchester, in the 5 county of Lancaster, England, (whose post-office address is "Boothdale," Fairfield, Manchester, in the county of Lancaster, England,) have invented certain new and useful Improvements in and Relating to Steam- 10 Superheaters for Locomotive and other Smoke-Tube Boilers; and I do hereby declare the following to be a full, clear, and exact description of the invention, such as will enable others skilled in the art to which 15 it appertains to make and use the same.

This invention relates to improvements in steam superheaters for boilers of the smoke tube type and is more particularly designed for use on locomotives.

20 In superheaters of the kind in which superheating pipes are placed in enlarged smoke tubes disposed among the ordinary smoke tubes of the boiler the ends of the superheating pipes being connected to a header, it is very desirable to provide a 25 means for protecting the superheating pipes from damage by heat when the regulator is closed and steam is not passing through them to the cylinders, as for instance, in the 30 case of a locomotive boiler, at such times as the engine is stopped or when steam is shut off from the engine cylinders when the locomotive is traveling down an incline. This has usually been effected by means of a 35 mechanical damper which covers the ends of the enlarged smoke tubes at their smoke box ends, the damper forming in some instances a part of a chamber which incloses the ends of the superheating pipes extending from 40 the ends of the smoke tubes to the header. Such dampers have been arranged to open automatically when steam is admitted to the superheater and to close when steam is shut off from the said superheater by the closing 45 of the regulator. Sometimes the dampers have been arranged to be worked by hand only. Whichever arrangement be used the presence of the damper and its adjunctive parts forms a serious obstruction to access 50 to the ends of the enlarged smoke tubes and of the superheating pipes, in addition to being costly.

The present invention has for its object to provide an arrangement whereby the super- 55 heating pipes will be protected from damage by heat when steam is not passing through

them to the cylinders and this protection obtained without the employment of a mechanical damper or the like mechanical contrivance in the smoke box.

According to this invention there is provided across the smoke box ends of each row of enlarged smoke tubes containing the superheating pipes a steam pipe connected to the steam space of the boiler and from 60 which steam pipes a small jet of steam is delivered centrally between the longitudinal portions of the superheater elements or pipes into the smoke box end of each enlarged smoke tube when the regulator is closed and 65 steam is cut off from the superheater. This 70 jet of steam will be so proportioned as not to be powerful enough to induce a draft along the tube in the direction of the fire box, but will only be sufficiently powerful 75 to neutralize the draft caused by the blower. If the draft caused by the blower be so neutralized it will be clear that the fire gases will not pass along the enlarged smoke 80 tubes and overheat the superheating pipes. The small jet of steam in effect introduces 85 a plug of steam into the end of the enlarged smoke tube and this plug is renewed as fast as the smoke box suction withdraws it so long as the regulator valve be closed and steam admitted to the above mentioned 90 steam pipes across the smoke tubes.

As the smoke box suction of a locomotive when steam is shut off depends practically entirely on the steam blower the strength of 90 the steam jets introduced into the ends of the enlarged smoke tubes containing the superheating pipes can readily be proportioned to that of the blower by taking their steam from a branch on the blower supply pipe. 95

In the preferred arrangement according to this invention the steam jet nozzles are fixed into short branches taken from the steam pipes extending across the ends of the enlarged smoke tubes and where a superheater element having four longitudinal portions or pipes placed in each smoke tube two washers are mounted on each jet pipe or nozzle and take between the four portions of the superheater element so as to insure 105 each jet pipe being central between the superheater pipes to thereby prevent any cutting of the pipes by the steam jets.

The invention is illustrated in the accompanying drawings, in which,—

Figure 1 shows in front elevation, and Fig. 2 in cross sectional elevation, the header

in the smoke box, the superheater elements or pipes, and some of the smoke tubes of a smoke tube type of superheater applied to a boiler of the locomotive type, provided with a "damper" according to this invention. Figs. 3 and 4 are views, on a larger scale, of one of the "damper" jets; Fig. 5 is detail view of the connection of the "damper" steam pipe to its steam supply, and of a means of positioning and supporting said "damper" steam pipe, and Fig. 6 is a view on an enlarged scale and partly sectional showing the position a blower jet occupies in relation to the component longitudinal pipes or portions of a superheater element.

Like reference symbols indicate like parts in the several figures of the drawings.

Referring to the drawings, 1 is the smoke box tube plate and 2 the header or steam collector of the superheater, 3 being the superheater elements or pipes and 4 the enlarged smoke tubes in which said elements are placed.

5 are ordinary smoke or fire tubes or flues of the boiler.

6 is a pipe connected to a suitable steam supply pipe, which supply pipe may be and preferably is the steam supply pipe to the usual steam blower of the locomotive. The pipe 6 is connected by a pipe 7 to a number of cross pipes 8 arranged at the smoke box ends of the enlarged smoke or fire tubes 4, and at each enlarged smoke tube 4 a suitable short branch is taken from the pipe 8 in each of which branches is screwed or otherwise mounted a steam jet nozzle 9.

It will be seen that the piping of the "damper" according to this invention consists of short lengths of standard gas or other pipe of suitable diameter coupled by T's and "elbows," and at suitable places (as at 10, 10 Fig. 1) union joints are provided to facilitate the work of taking the "damper" apart. In the arrangement shown in the drawings the nozzles 9 are connected to the pipes 8 as follows:—Opposite each enlarged smoke tube 4 the pipes 8 are provided with T-pieces 11, to the vertical branch 12 of each of which an elbow 13 is connected by a nipple. Into the horizontal portion of the elbow 13 the end of the nozzle 9 is screwed, a bushing being first screwed into the elbow if necessary owing to difference in diameter. In order that the center line of the nozzle 9 shall be kept parallel to the center lines of the longitudinal portions of the superheater element or pipe 3 and that said nozzle shall also be kept in position centrally between said longitudinal portions, two washers 14, 15 are secured on said nozzle 9 (for instance, the washer 14 is first passed about said nozzle 9 into position, a distance piece or thimble 16 being next placed in position and the washer 15 finally screwed on to said nozzle)

and these washers take between the said longitudinal portions of the element 3 as shown. If found necessary or desirable a segmental portion may be removed from the upper part of washer 14 so that said washer 70 may have a greater bearing against the underside of that return bend fitting of the element which is above the said washer.

To position the pipes 6, 7 and to afford support thereto, a screwed plug 17 is provided on the smoke tube plate 1 being secured to the latter by a flange connection 18 and on to the plug 17 the T piece 19, which connects pipes 6 and 7, is screwed as shown. Plugs 20, or other closing means, 80 may be employed to close the ends of the cross pipes 8. The cross pipes 8 might be arranged to rest on the superheater elements 3 or other means might if desired be employed for supporting them.

When steam is admitted to pipe 6, as when the blower valve is actuated to place the blower in action, it passes to the cross pipes 8 and jets or nozzles 9 and issuing therefrom it acts in the manner hereinbefore set forth.

What I claim as my invention and desire to secure by Letters Patent is:—

1. In a locomotive or like boiler, the combination of a multiplicity of enlarged smoke or fire tubes, superheater elements or steam pipes extending into the said fire tubes, a plurality of branch steam pipes opposite the outlet ends of the said fire tubes, a plurality of steam jet nozzles connected with the said branch pipes, one nozzle for each of said fire tubes and the outlet ends of the said nozzles projecting into the outlet ends of the said fire tubes, a steam pipe connection from the boiler steam space to the said branch steam pipes and means for controlling the admission of steam to the said pipe connection from the boiler and to the branch steam pipes and nozzles, substantially as and for the purposes set forth.

2. In a locomotive or like boiler, the combination of a multiplicity of enlarged smoke or fire tubes, superheater elements or pipes extending into the said fire tubes, a plurality of branch steam pipes opposite the outlet ends of the said fire tubes, a plurality of steam jet nozzles connected with the said branch pipes one nozzle for each enlarged fire tube and the outlet ends of the said nozzles located centrally between the longitudinal portions of the superheater elements, a steam pipe connection from the boiler steam space to the said branch steam pipes, and means for controlling admission of steam to the said pipe connection from the boiler and to the branch steam pipes and nozzles connected thereto, substantially as and for the purposes set forth.

3. In a locomotive or like boiler, the combination of a multiplicity of enlarged smoke

or fire tubes, superheater elements or pipes extending into the said fire tubes, a plurality of branch steam pipes opposite the outlet ends of the said fire tubes, a plurality of 5 steam jet nozzles connected with the said branch pipes, one nozzle for each enlarged fire tube and the outlet ends of the said nozzles located centrally between the longitudinal portions of the superheater elements, 10 and a steam pipe connection from the blower steam supply pipe to the said branch steam pipes, substantially as and for the purposes set forth.

4. In a locomotive or like boiler, the combination of a multiplicity of enlarged smoke or fire tubes, superheater elements or steam pipes extending into the said fire tubes, a plurality of horizontally arranged steam pipes, a vertical steam pipe connecting the 20 said horizontal pipes, downwardly projecting pipe connections to the said horizontal pipes, steam jet nozzles connected to the said downwardly projecting pipes and in axial alinement with the respective fire tubes and 25 having their outlet ends located centrally between the longitudinal portions of the superheater elements, and a steam pipe connection from the blower steam supply pipe to the said horizontal and vertical steam 30 pipes and nozzles, substantially as and for the purposes set forth.

5. In a locomotive or like boiler the combination of a multiplicity of enlarged smoke or fire tubes, superheater elements or pipes 35 extending into the said fire tubes, a plurality of branch steam pipes opposite the outlet

ends of the said fire tubes, a plurality of steam jet nozzles connected with the said branch pipes one nozzle for each enlarged fire tube and the outlet ends of the said nozzles located centrally between the longitudinal portions of the superheater elements, a steam 40 pipe connection from the boiler steam space to the said branch steam pipes, and means for controlling admission of steam to the said pipe connection from the boiler and to the branch steam pipes and nozzles connected 45 thereto, substantially as and for the purposes set forth.

6. In a fire-tube boiler, the combination, with a fire-tube open at each end, and a superheater element arranged at the outlet 50 end of the fire-tube and projecting longitudinally within it; of a steam jet tube arranged longitudinally within the outlet end portion of the fire-tube and operating to prevent the said superheater element from 55 becoming overheated when not in operation, the steam being delivered from the said jet tube in the opposite direction from the flow of the products of combustion in the fire-tube and being ultimately discharged with 60 them from the outlet end of the fire-tube.

In testimony whereof I affix my signature in presence of two witnesses.

JOHN GEORGE ROBINSON.
